CLAIM

The ornamental design for a hair elastic, as shown and described.

DESCRIPTION

FIG. 1 is a top perspective view of a hair elastic, showing my new design;

FIG. 2 is a right-side elevation view thereof;

FIG. 3 is a left-side elevation view thereof;

FIG. 4 is a front side elevation view thereof;

FIG. 5 is a rear elevation view thereof;

FIG. 6 is a top plan view thereof;

FIG. 7 is a bottom plan view thereof; and,

FIG. 8 is a front cross-sectional view thereof, taken along line 8-8 shown in FIG. 6.
